Design No. 761.

Jas M. Thompson
Design for Bricks
Patented Feb 29, 1856.

UNITED STATES PATENT OFFICE.

JAMES M. THOMPSON, OF PHILADELPHIA, PENNSYLVANIA.

DESIGN FOR A MOLDED BRICK.

Specification forming part of Design No. 761, dated February 12, 1856.

To all whom it may concern:

Be it known that I, JAMES M. THOMPSON, of the city of Philadelphia, in the county of Philadelphia and State of Pennsylvania, have invented or produced a new and original Design for a Brick; and I do hereby declare that the following is a full and exact description of the same, reference being had to the annexed drawings.

The side of the brick which is intended to be shown when laid in a wall contains sunken impressions, as represented in A, B, and C of the drawing, and the edges of the same side are also sunken, as represented in letter D of

the drawing. The other sides and ends of the brick are of a plain or even surface, as shown in letters E and F, representing a side and end of the brick.

What I claim in terms characteristic of the design is—

The shape of the brick and the ornaments that are on the brick, as represented and described in this specification and in the annexed drawing.

JAMES M. THOMPSON.

Witnesses:

JOHN S. HOLLINGSHEAD,
SAML. GRUBB.
